[57] CLAIM

The ornamental design for a return top, as shown.

DESCRIPTION

FIG. 1 is a perspective view showing my new design for a return top;

FIG. 2 is a side elevational view thereof;

FIG. 3 is a side elevational view thereof;

FIG. 4 is an end elevational view thereof;

FIG. 5 is an end elevational view thereof;

FIG. 6 is a top plan view thereof; and

FIG. 7 is a bottom plan view thereof;

FIG. 8 is a perspective view showing an alternative embodiment of my new design for a return top;

FIG. 9 is a side elevational view of the design of FIG. 8;

FIG. 10 is a side elevational view of the design of FIG. 8;

FIG. 11 is an end elevational view of the design of FIG. 8;

FIG. 12 is an end elevational view of the design of FIG. 8;

FIG. 13 is a top plan view of the design of FIG. 8; and,

FIG. 14 is a bottom plan view of the design of FIG. 8.
